UNITED STATES PATENT OFFICE.

MAURICE M. GLASSER, OF CHARLESTON, SOUTH CAROLINA.

CEILING FAN.

Application filed October 7, 1922. Serial No. 593,031.

To all whom it may concern:

Be it known that I, MAURICE M. GLASSER, a citizen of the United States, and a resident of Charleston, in the county of 5 Charleston and State of South Carolina, have invented certain new and useful Improvements in Ceiling Fans, of which the following is a full, clear, and exact description, reference being had to the drawings, 10 forming a part of this specification.

This invention relates to improvements in ceiling fans.

In my prior Patent No. 1,409,090, dated March 7, 1922, there is disclosed a ceiling 15 fan embodying means for alternately increasing and decreasing the area affected by the blasts of air created by the revolving fan blades. This result is obtained in said fan by oscillating or swinging the blades alternately 20 in opposite directions transversely of the horizontal plane in which they revolve.

The present invention has for its object to improve upon the mechanism for obtaining the oscillatory motion of the revolving 25 fan blades.

In the accompanying drawings—

Figure 1 is a side view of a fan embodying the present improvements;

Fig. 2 is a top plan view of the fan, and 30 Fig. 3 is a vertical sectional view of a portion of the fan structure showing the mechanism for oscillating the fan blades.

As illustrated in the drawings, a casing 10 is provided for the fan motor, preferably 35 an electric motor, and said casing and motor are rotatably mounted on the lower end of a depending shaft 11 whose base 12 is secured to the ceiling. Shaft 11 may be made hollow and the lead wires for supplying cur- 40 rent to the motor may extend therethrough.

Extending radially from the casing or rotor of the motor 10 is a series of fan blades 13 adapted to revolve with said casing or rotor 10 and, as in my prior patent 45 before mentioned, the blades are pivotally supported at their inner ends by suitable pivotal connections 14 that will permit them to swing up and down or transversely of the plane in which they revolve.

50 In accordance with the present invention, however, a vertically disposed worm 15 is rigidly mounted on the shaft 11 and surrounding and in mesh with said worm is a series of gear wheels 16 rotatably mounted on 55 axes parallel to the pivotal centers of blades 13 and corresponding in number to the num-

ber of said blades. Said wheels 16 are journaled in a suitable supporting frame journaled on shaft 11 to permit said wheels to revolve bodily about worm 15, thereby imparting a rotary movement to the wheels about their journals and this rotary movement of the wheels is utilized to effect the oscillatory motion of blades 13.

Preferably each blade 13 of the fan has 60 one end of a link 17 pivotally connected thereto while the opposite end of each link is pivotally connected to a crank pin or one of the gear wheels. As the blades 13 are caused to revolve by the motor they will, 65 through the link connection 17, cause wheels 16 to travel around worm 15 with the result that the wheels will be rotated on their own axes and this rotary movement of the gear 70 wheels will gradually raise and lower the 75 blades relatively to the plane in which they revolve, depending upon the direction of movement of the ends of the links that are eccentrically attached to the wheels. In other words, as will be apparent, one complete revolution of one of the wheels 16 will cause the eccentrically attached end of link 80 85 85 to make one complete revolution about the axis of that wheel and as the link moves up and down during that revolution the connected fan blade will be moved correspondingly.

To permit adjustment of the throw of the fan blades 13 relatively to the plane in which they revolve, each gear wheel 16 is 90 preferably provided with a series of holes or crank pin sockets 18 arranged different distances from the axis of the wheel and the upper end of link 17 may be attached at any one of the sockets by a crank pin 19. 95 Other forms of detachable connections for the links and wheels will readily suggest themselves but the form shown is preferred as it has practically no weakening effect on the wheels. This connection also permits the 100 blades to be adjusted with respect to each other so as to permit one blade to move upwardly as the opposite blade moves downwardly or they can be adjusted to move in the same direction simultaneously.

105 While the gear wheels 16 may be carried in any desired form of supporting frame, so long as they are arranged on axes parallel to the pivotal centers of blades 13 and are free to travel around worm 15, said wheels 110 are preferably journaled in bearings formed in depending forked arms 20 adjustably se-

cured at their upper ends to a disk 21 rotatably mounted on shaft 11 or, as shown, on the worm screw which is adjustably mounted on shaft 11.

5. The present mechanism is cheap, simple to install and presents the advantage of a smooth, regular action in shifting of the angles of the blades without producing noise when the change in direction of movement 10 occurs.

Obviously any type of motor with internal or external rotors may be employed as this forms no part of the present invention.

What is claimed is:

15 1. In a ceiling fan, the combination of a motor and its rotor, a series of hinged blades carried by said rotor, a shaft supporting said motor and blades, and means carried by the shaft and connected to said

20 blades for swinging said hinged blades transversely of the plane in which they revolve, said means, with the exception of the connections with the blades, being fixed longitudinally of the shaft.

25 2. In a ceiling fan, the combination of a motor and its rotor, a series of hinged blades carried by the rotor, a shaft supporting said motor and blades, and actuating means carried by the shaft and connected to the blades for swinging the hinged blades, there being adjustable connections between said actuating means and blades, said actuating means with the exception of the connection with the blades being fixed longitudinally of the 35 shaft.

30 3. In a ceiling fan, the combination of a supporting shaft, a motor and its rotor carried on the shaft, blades hinged to the rotor, a worm on said shaft, a series of rotatable 40 gears meshing with said worm, and connections carried by said blades for moving the worm and the series of gears relatively to one another for rotating the gears and thereby oscillating the blades.

45 4. In a ceiling fan, the combination of a supporting shaft, a motor on the shaft, blades hinged to the rotor of the motor, a

worm rigidly mounted on the shaft, a series of worm gears meshing with said worm, and connections between the blades 50 and gears whereby rotation of the blades will revolve said gears around the worm and oscillate the blades.

5. In a ceiling fan, the combination of a supporting shaft, a rotatable casing, radially 55 extending blades carried by the casing and hinged thereto to swing transversely of the plane in which they revolve, and means carried by the shaft and connected with the blades and controlled by the revolution of 60 the blades for swinging said blades, said means with the exception of the connection with the blades being fixed longitudinally of the shaft.

6. In a ceiling fan, the combination of a supporting shaft, a rotatable casing, a series of blades adapted to revolve with the rotating casing and pivoted to swing transversely of the plane in which they revolve, 70 a worm mounted on said shaft, a series of worm gears meshing with said worm and rotatable on axes parallel to the pivotal centers of the blades, and connections between said blades and gears for revolving the gears around the worm, said 75 connections being attached to the gears eccentrically of the centers of the gears whereby rotation of the gears will oscillate the blades on their pivotal centers.

7. In a ceiling fan, the combination of a 80 supporting shaft, a rotatable casing, a series of blades adapted to revolve with the rotating casing and pivotally mounted to swing transversely of their plane of rotation, a worm mounted on the shaft, a series of gears 85 meshing with the worm and adapted to travel around said worm, each of said gears having a series of sockets arranged eccentrically of its center, a link connected to each blade, and means for detachably connecting each blade and link to one of said 90 gears at one of the sockets in the latter.

MAURICE M. GLASSER.
